Attorneys.

UNITED STATES PATENT OFFICE.

EUGENE L. FRANTZ, OF SWEET VALLEY, PENNSYLVANIA, ASSIGNOR OF
ONE-HALF TO F. N. RUGGLES, OF SAME PLACE.

DRILL.

SPECIFICATION forming part of Letters Patent No. 399,142, dated March 5, 1889.

Application filed March 20, 1888. Serial No. 267,850. (No model.)

To all whom it may concern:

Be it known that I, EUGENE L. FRANTZ, a citizen of the United States of America, residing at Sweet Valley, in the county of Luzerne and State of Pennsylvania, have invented certain new and useful Improvements in Drills, of which the following is a specification, reference being had therein to the accompanying drawings.

10 This invention pertains to certain new and useful improvements in drills, having for its object the provision of simple and highly-efficient means for securing or adjusting the drill at the desired height and for tilting and operating the same at the desired angle, and also for providing means for effecting the withdrawal of the article operated upon.

15 The invention, therefore, comprises the detail construction, combination, and arrangement of parts, substantially as hereinafter fully set forth, and particularly pointed out in the claims.

20 In the accompanying drawings, Figure 1 is a view in perspective of my invention. Fig. 2 is a vertical longitudinal sectional view, and Fig. 3 is a detail view.

25 Referring to the drawings, A designates the barrel or cylinder, in the ends of which are secured threaded rings or collars a a. B is a second screw-threaded barrel or cylinder designed to be inserted through the barrel or cylinder A and engage the threaded rings or collars a, as shown. Through this second barrel or cylinder, B, is passed the 30 drill-shaft C, one end of which is provided with a crank-handle, b, and to its other forward end is secured, by means of a collar, b', the inner end of the drill-bit b².

35 D is the adjustable stand for securing the drill at the desired height and to permit the same to have a pivotal movement at an angle to a horizontal plane. This stand consists of two telescoping rods, d d', the former being inserted down over the latter and held at the 40 desired point of adjustment by means of a thumb-screw, d², passed through an aperture in the lower end thereof. The inner rod, d', at its lower end has a foot, d³, from which teeth or prongs project, which aid in holding 45 the stand in position, said foot being generally covered with stone to hold the same steady.

To the upper end of the outer rod, d, is pivotally secured a hoop or band, E, designed to encircle and incase the barrel A. The opposite parallel ends of said hoop or band are secured against the rod d' by a pivotal bolt, e, passed through coincident apertures. By this arrangement the drill can be secured at the desired height, and can then be tilted or brought into the desired angle in performing 60 the drilling operation, which is effected by turning the hand-wheel B' upon said cylinder or barrel—the ordinary way of operating the latter.

To the outer forward end of the outer barrel, A, I have secured two cheeks, F F, having horizontal apertures, wherein are designed to be secured the inner ends of grappling-hooks G, by means of short pins g, passed through coincident holes of said cheeks and 70 hooks. The object of this construction is that after the drilling operation is completed and the drill-bit is removed and the barrel B screwed so as to move rearwardly by the hand-wheel upon said cylinder or barrel the article 75 operated upon can be removed by means of the grappling-forks either passed around the same or connected to chains or cables tied around such article, and by reason of the pivotal stand said article can be swung around 80 and deposited at the desired point.

This invention is designed especially for use in connection with drills for drilling holes in boilers, tanks, &c., and to accomplish such drilling the drill is firmly secured at the desired point by means of the foot d³ of stand D, which is additionally held in position by rocks or other weight placed on said foot. During the drilling operation the arms G perform no especial office and are generally swung 90 back; but at the completion of the drilling, when it is desired to move the boiler, tank, &c., operated upon, the same can be readily done by tying a rope or cable around the same and then swinging around arms G, so that 95 their ends will overlap beneath said rope or cable, the weight of the boiler or tank serving to hold said arms as against movement. Thus secured, the boiler or tank can be moved laterally to any desired point or raised or lowered within the length of the drill-barrel A.

100 The advantages of my invention will be ap-

parent to those skilled in the art to which it appertains, and it will be seen that the same embodies advantages in points of simplicity, durability, and general efficiency.

5 I claim as my invention—

1. As an improvement in drills, the combination, with the drill-shaft and the barrel or cylinder, of the telescoping rods, one of which has a lower forked end and the other a set-
10 screw bearing against said rod, the hoop or band encircling said barrel or cylinder, and the bolt passed through lower parallel ends of said hoop or band, substantially as shown and described.

2. In a drill, the combination, with the barrel or cylinder having the apertured cheeks at its forward end, of the grappling-forks pivotally secured to said cheeks, substantially as shown and described.

15 In testimony whereof I affix my signature in presence of two witnesses.

EUGENE L. FRANTZ.
